OTHER PUBLICATIONS

The disclosed photograph shows an original equipment Toyota shift cable bushing.

Primary Examiner — Susan E Krakower

Assistant Examiner — Jerry Shiuan-Hua Hsu

(74) *Attorney, Agent, or Firm* — Volpe and Koenig, P.C.

(57) **CLAIM**

The ornamental design for a shift cable bushing, as shown and described.

DESCRIPTION

FIG. 1 is a perspective view of our shift cable bushing; FIG. 2 is a front elevation of the shift cable bushing in FIG. 1;

FIG. 3 is a rear elevation of the shift cable bushing in FIG. 1;

FIG. 4 is a right side elevation of the shift cable bushing in FIG. 1;

FIG. 5 is a left side elevation of the shift cable bushing in FIG. 1;

FIG. 6 is a top plan view of the shift cable bushing in FIG. 1; and,

FIG. 7 is a bottom plan view of the shift cable bushing in FIG. 1.

The broken lines illustrate portions of the shift cable bushing that form no part of the claimed design.

1 Claim, 5 Drawing Sheets
